UNITED STATES PATENT OFFICE.

JAMES E. SMITH, OF ST. LOUIS, MISSOURI, ASSIGNOR OF ONE-THIRD TO GEORGE SEPER,
OF ST. LOUIS, MISSOURI.

CORN-CUTTER.

1,361,633.

Specification of Letters Patent. Patented Dec. 7, 1920.

Application filed September 13, 1919. Serial No. 323,638.

To all whom it may concern:

Be it known that I, JAMES E. SMITH, a citizen of the United States, residing at the city of St. Louis, in the State of Missouri, have invented certain new and useful Improvements in Corn-Cutters, of which the following is a specification.

This invention is an apparatus for cutting broom corn, Kafir corn, sugar cane, sorghum, or the like. It is sometimes briefly denominated a corn sled. The objects of this invention are safety for those engaged in cutting corn and the like, economy in the number of men employed for that purpose, and an increase of the quantity cut as compared to the time or labor expended.

In the accompanying drawings forming part of this specification, in which like numbers of reference denote like parts wherever they occur,

Figure 1 is a top-plan view;

Fig. 2 is a side elevation;

Fig. 3 is a front elevation;

Fig. 4 is a sectional view on the line 25 4—4 in Fig. 1;

Fig. 5 is a plan view of the draft-rigging; and

Fig. 6 is a bottom plan view showing the means for making one of the runners adjustable.

Heretofore it has been customary to build sleds like this with seats for two operators and knives on both sides of the sled. The seats for the workmen were located between the cutters. In practice, this has proved a very dangerous location for the workmen, and, by reason thereof, many persons have been injured, some of them fatally. A frightened team or a jolt over a stump or rock has in many instances been known to throw the operator down upon the cutter-blade with one of his feet or legs upon the ground in advance of the cutter, which was dragged over it by the team. In contradistinction to the foregoing, the seat 1 in this present construction is located off to one side from the single cutter-blade 2 and in such a position as to enable the operator to save himself without coming into contact with the blade 2 even in case of accident.

In the former devices of this character, it was customary to use a team of horses, whereas with this device a single horse will suffice, which results in great economy.

The said former devices forced the operators to lean out in opposite directions from the sled and in their arms to gather in the stalks of grain falling after being cut and to hold in their arms the stalks thus gathered either until the end of a row or until the arms became too full to hold any more; whereupon it would be necessary to stop the sled and free the arms of the operators and to make a new beginning.

This present device provides a flexible resilient curved arm 3, which holds the stalks on one side while frame 4 holds them on the other side, until the forward movement of the sled 5 brings the knife 2 into contact with the stalks, which have been guided thereto by the arm 3, the frame 4, and, in part, by the cam-part 6 of the arm 3. The severed stalks slide off the tip 7 of arm 3, being at that time held at their lower ends in pocket 8 and the tip 7 gives them an impulse at the top that throws them forward into the cradle composed of the frames 9 and 10.

The draft-rigging is attached through eyes formed by straps 11 and is composed of links 12 having eyes 13 and 14 and links 15 having eyes 16, the links 12 and the links 15 being connected by clevises 17 and there being a larger clevis 18 at the opposite end of links 15 and connecting the same.

The arm 3 is socketed in projection 19 from runner 20, which is a third or separate runner from the main runners 21 of the sled. Runner 20 projects at angles away from the adjoining runner 21, so as to form a tapering pocket for the stalks to be cut, gradually drawing them closer together as the sled progresses forward to bring knife 2 into cutting contact with them.

One of the runners 21 is foreshortened, as plainly shown in Fig. 1, while its mate extends to about the rear of the sled. As plainly shown in Fig. 2, the rear part of runner 20 rests upon the ground like the long runners 21, and this height for runner 100

20 continues to about the point where foreshortened runner 21 terminates, while forwardly thereof runner 20 tapers upwardly and projects like an arm.

5 The pocket 8 is formed by making a recess or cut in the sled body, and the sled body at 22 is wider than the forward part of the sled body, so as to receive and hold the knife 2 and present the same at the rear 10 of pocket 23, as well as at the rear of pocket 8.

The knife 2 is preferably set at a slant, as plainly shown in Fig. 1, so as to allow the grain stalks that approach it through 15 pocket 23 to receive a sliding or glancing cut.

The runner 20 is made adjustable, so that it can occupy the position shown either in the full lines or in the dotted lines in Fig. 1.

20 For this purpose, it is provided with a slot 24, through which brace 25 is securely fastened to the runner 21 on the opposite side of the sled and, also, to the rear body-portion 22. A brace 26 is likewise fastened to 25 the same runner 21 and to the body 22 and to brace 25 and to one end of the said brace 26. The runner 20 is pivoted at 27. The slot 28 is made of such size, as is also slot 24, that the movement of runner 20, inwardly 30 to occupy the dotted-line position in Fig. 1 or in the reverse direction, does not cause braces 26 and 25 to bind on their respective slots 28 and 24.

In order that runner 20 may be held quite 35 rigid, it is fastened by bolts 29 to rack 34 by means of the depending arm 31 integral therewith. By bolts 32, that pass through slot 33 in rack 30, the said rack is bound into close engagement with the teeth on notched 40 plate 34, fastened to the underneath side of body 22.

Rack 30, is above the notched plate 34, and the teeth on the underneath side of rack 30 engage the teeth or notches on the upper 45 side of plate 34.

It is to be borne in mind, that instead of employing runners such as described hereinbefore, the device may be caused to function equally well by the substitution of 50 wheels, or other mechanical equivalents.

Having thus described this invention, I hereby reserve the benefit of all changes in form, arrangement, order, or use of parts, as it is evident that many minor changes may 55 be made therein without departing from the spirit of this invention or the scope of the following claims.

I claim:

1. In a device of the character described, 60 the combination of a sled proper, an additional runner attached thereto and projecting away therefrom at an acute angle, the forward part of the said runner being above the ground and curved upwardly and the 65 rear part of the said runner extending to

the ground, a pocket cut in the sled body, and a knife within the said pocket.

2. In a device of the character described, the combination of a sled proper, an additional runner attached thereto and projecting away therefrom at an acute angle, the forward part of the said runner being above the ground and curved upwardly and the rear part of the said runner extending to the ground, a pocket cut in the sled body, and a knife within the said pocket, the said knife extending from within the said pocket outwardly to the said additional runner. 75

3. In a device of the character described, the combination of a sled proper, an additional runner attached thereto and projecting away therefrom at an acute angle, the forward part of the said runner being above the ground and curved upwardly and the rear part of the said runner extending to the ground, a pocket in the sled body, and a knife within the said pocket, the said knife extending from within the said pocket outwardly to the said additional runner and being slanted forwardly relative to a transverse section of the sled. 80

4. A sled of the character described having a pair of runners in the forward part, one of which extends to approximately the rear end of the sled and the other of which 95 is foreshortened, a third runner which is of height equal to the said foreshortened runner in the rear part of the said third runner and forward thereof tapers upwardly, a pocket in the main body of the sled, and a knife within the said pocket. 100

5. In a device of the character described, the combination of a body, a runner, the said runner having slots therein, a brace or braces borne by the said body and entering the said 105 slots, a notched plate fastened to the said body, a rack attached to the said runner and having a slot therein, and bolts for locking the said rack to the said plate.

6. In a device of the character described, the combination of a body, a runner, the said runner having slots therein, a brace or braces borne by the said body and entering the said 110 slots, a notched plate fastened to the said body, a rack attached to the said runner and having a slot therein, and bolts for locking the said rack to the said plate, the said runner being in pivotal connection with a brace attached to the said body. 115

7. In a device of the character described, a 120 body having a laterally extended pocket formed in the rearward portion thereof, a runner carried by said body and angularly adjustable with relation thereto, cutting means carried by the body adjacent the rear side of the pocket, and a cradle on the body directly forward of said pocket, and means for receiving and retaining the matter cut by the cutting means as the same falls onto said body. 125

8. In a device of the character described, the combination of a body, a runner having slots therein, a brace on the body entering said slots, a notched plate secured to the body adjacent one side thereof, a slotted arcuate plate attached to said runner, and a means adjacent the plate and engageable through and with the arcuate plate for locking the same to said plate, the runner being in pivotal relation to the brace on said body. 10
- 5 In testimony whereof I hereunto affix my signature.

JAMES E. SMITH.
